UNITED STATES PATENT OFFICE

SAMUEL DOSICK, OF PROVIDENCE, RHODE ISLAND

PISTOL CHARM

Application filed October 23, 1929. Serial No. 401,652.

My invention relates to pistol charms simulating revolvers and of the type wherein the barrel is capable of being depressed or broken down, and the cylinder is nonrotary and is equipped with a single chamber for the reception of an explosive cap or cartridge fired by the impact of a hammer upon a firing pin in the cartridge.

The essential objects of my invention are to insure the barrel casing against accidental escape from locked position; to prevent the barrel from assuming an indefinite or unpredictable position when the barrel casing is unlocked or broken down; to prevent the trigger from assuming an excessively advanced position whereby it will become cramped in the path of the cylinder; and to enable the barrel casing and frame to be formed or bent up from sheet metal blanks whereby expense of material and labor may be avoided.

To the above ends primarily my invention consists in such parts and in such combinations of parts as fall within the scope of the appended claims.

In the accompanying drawings which form a part of this specification,

Figure 1 is a plan view of the blank from which the barrel casing is formed,

Figure 2, a perspective view of the complete barrel casing,

Figure 3, a plan view of the blank from which the carrier frame is formed,

Figures 4 and 5, a perspective view and plan view respectively of the carrier frame,

Figure 6, a detail view of the handle skeleton plate,

Figures 7, 8, 9, and 10, similar views of the barrel supporting spring, the cylinder, a cartridge, and the hammer respectively,

Figure 11, a side elevation of the pistol charm,

Figures 12 and 13, longitudinal sections of the same in locked position and extreme released positions respectively, and

Figure 14, a fragmentary side view of the pistol charm showing a position assumed by the parts during the interlocking operation.

Like reference characters indicate like parts throughout the views.

In carrying out my invention, there is cut from thin sheet metal a blank 17, shown in Figure 1, comprising a transversely oblong portion 18 with rectangular extensions 20 upon its top and bottom provided with apertures 21. This blank or plate has centrally of one of its edges a lateral oblong extension 22 provided with a rectangular recess 23 in its end. When bent up this blank forms a barrel casing 17 including a tubular sleeve 18 with depending rectangular lugs 20 adjacent or in contact with each other provided with apertures 21, while a horizontal rearwardly directed flat arm 22 is provided with a recess 23 whereby are formed fingers 24 with slightly rounded or convex end edges 25, all as shown in Figure 2. Fixed by solder or otherwise in the sleeve 18 is a barrel 27 whose inner end enters an annular recess 28 in the forward end of a cylinder 29 fixed by solder to the lower face of the arm or extension 22 of the sleeve 18. The bore of the barrel is continuous with a chamber 30 in the upper portion of the cylinder, of which chamber the recess 28 is an enlargement. A slot 31 in the upper portion of the inner end of the cylinder, as shown in Figure 12, registers with the recess 23. The slot 31 is for the purpose of permitting the passage therethrough of the firing pin 32 of a cartridge 33 shown in Figure 9.

From a sheet of thin metal is cut by suitable tools a blank or plate 36 of the form shown in Figure 3 consisting of a substantially rectangular central portion 37 upon which is defined by spaced longitudinal scores 38 lateral portions 39 and a central web portion 40. There is a perforation 41 in the portion 40, and diverging lugs 43 provided with holes 44 extending from the forward end of the blank portions 39. Extending rearwardly and laterally from the rear ends of the portions 39 are wings 46 of identical form provided with straight forward edges 47 provided at their end portions with cavities 48 forming terminal slightly yielding lugs 49 with rounded or convex ends 50. Quadrilaterally arranged in each wing are openings 51, 52, 53 and 54. The described blank is by suitable tools bent up into the form

shown in Figures 4 and 5, wherein the wings 46 form parallel vertical side walls integral with whose forward ends are parallel supporting arms 39 with upwardly inclined bearings 43 upon their free ends. A web portion 40 is integral with the bottoms of the arms. A pivot pin 56 passes through the apertures 21 of the lugs 20 and the holes 44 of the bearings 43, and the barrel casing 17 and attached parts are held in normal locked position by the registration of the fingers 24 in the cavities 48. The casing and the parts carried thereby are further supported by a flat spring member 58, shown in detail in Figure 7, comprising a broad rectangular body portion 59 of sufficient width to rest upon the upper edges of the arms 39, a forwardly extending reduced portion 60 normally abutting against the horizontal lower edges 61 of the lugs 20, and a rearwardly projecting retracted portion 63 extending a slight distance between the walls 46. The member 58 is retained in position by a rivet 65 passing through the perforation 41 in the web 40 and a perforation 66 in the body portion 59 of the spring member.

The hammer 68, which is shown in detail in Figure 10, is provided with two angular recesses 69 and 70, one in advance of the other, whereby is formed a posterior acute angular projection 71 and a posterior shoulder 72. It is also provided with a perforation 73 adjacent the recess 70 to receive therethrough the pivot rivet 75 extending into the openings 51 of the frame walls 46. In the openings 52 of the latter is a pivot rivet 76 extending loosely through an intermediate portion of a vertically disposed trigger 77 having adjacent the rivet a posterior shoulder 78. The upper end of the trigger normally extends into the recess 69, and the portion 63 of the spring 58 is slightly spaced from the forward edge of the trigger at a point above the horizontal plane of the pivot member 76, so as to constitute a stop in the path of the trigger when by an excessive pull thereon the latter would otherwise become cramped in the space normally occupied by the cylinder and the pistol become useless.

The skeleton handle plate 80, cut from a strip of thin sheet metal, is, as shown in Figure 6, provided with an elongated tapering slot 81 extending longitudinally from its upper end, and has projecting from its opposite end a lug 83 provided with a hole 84 for the reception of a chain attaching ring 85. In the upper end of the plate are spaced perforations 86 for the reception of rivets 87 located in the openings 53 and 54 of the enclosing side walls 46. A perforation 89 in an intermediate portion of the plate accommodates a rivet 90 which secures handle panels 91 to opposite sides of the handle plate. A folded expansion spring 92 for actuating the hammer and trigger comprises

a loop 93 seated in the lower end of the handle recess 81, an upper arm 94 terminating in the recess 70 and bearing against the posterior shoulder 72 of the hammer, and a lower shorter arm 95 whose end rests upon the shoulder 78 of the trigger. Normally the hammer projection bears against the rear upper portion of the trigger, as shown in Figure 12, but in nonfiring position the projection rests upon the top end of the trigger, as shown in Figure 13.

The rigid interlocking of the barrel casing with the carrier frame, which is one feature of this invention, is effected by means of the snug seating of the fingers 24 in the casing cavities 48. This is by reason of the forwardly directed tapering lugs 49 with rounded or convex forward ends and located immediately above the cavities 48; and by the rounded or convexed ends of the fingers 24 which are of such length as to extend within the slot after snapping by the lugs, in which position the fingers are snugly held between the lugs above, and the bottom walls 97 of the cavities, which in this instance extend forward slightly beyond the lugs 49. In Figure 14 in broken lines is shown the path of the fingers as they approach and slightly force rearwardly the intervening lugs 49 during the closing movement of the barrel casing.

The finger or forwardly extending portion 60 of the spring 58 while normally assisting to maintain the barrel horizontally is of greater importance in positively maintaining the barrel 27 in a predetermined position when the interlocking parts are released instead of permitting the barrel to laxly swing. In Figure 13 it will be observed that when the barrel in breaking down has described approximately an arc of ninety degrees the spring finger 60 presses against the forward edges 98 of the lugs 20, ninety degrees from the normally engaged edges 61.

The important function of the rearwardly directed projecting portion 63 of the spring 58 in relation to the trigger has been hereinabove adverted to.

It will be observed that the described pistol structure lends itself to the use of cut and bent up sheet metal blanks.

I claim:

1. In a pistol charm, a carrier frame including vertical parallel side walls provided in their forward ends with cavities, forwardly directed arms upon walls below the cavities, upwardly directed bearings upon the forward portion of the arms, a barrel casing comprising a sleeve, fingers supported by the sleeve registerable in the cavities, and depending rectangular lugs upon the bottom of the sleeve extending between the bearings, a barrel in the sleeve, a pivot pin in the lugs and bearings, and a horizontal flat spring comprising a portion fixed to the arms

and a free end portion in overlapping engagement with the edges of the lugs.

2. In a pistol charm, a carrier frame comprising interspaced side walls, forwardly directed arms integral with the lower portions of the walls, a barrel casing pivotally supported by the arms and engageable with the walls, a barrel in the casing, a pivot member in the lower portion of the side walls, a vertical trigger pivoted intermediate its length upon said member, and a spring fixed to the arms and normally out of engagement with the trigger projecting between the side walls in the path of the trigger above the plane of the pivot member.

3. As a new article of manufacture, a blank for a toy pistol carrier frame comprising a substantially rectangular central portion provided with spaced longitudinal scores defining lateral portions and a central web portion, diverging lugs upon the lateral portions at their forward ends provided with holes, and wings upon the other ends of the lateral portions provided with straight forward edges provided near their outer ends with cavities, and lugs extending from the edges adjacent the recesses.

In testimony whereof I have affixed my signature.

SAMUEL DOSICK.
